UNITED STATES PATENT OFFICE.

WILLETS MACOMBER, OF CHESTER, PENNSYLVANIA.

IMPROVEMENT IN SAD-IRONS.

Specification forming part of Letters Patent No. 152,137, dated June 16, 1874; application filed February 13, 1874.

To all whom it may concern:

Be it known that I, WILLETS MACOMBER, of Chester, in the county of Delaware and State of Pennsylvania, have invented certain new and useful Improvements in Sad-Irons; and I do hereby declare the following to be a full, clear, and exact description of the invention, such as will enable others skilled in the art to which it pertains to make and use it, reference being had to the accompanying drawings, which form part of this specification, in which—

Figure 1 is a vertical longitudinal section of my invention. Fig. 2 is a transverse section of slotted heater. Fig. 3 is a transverse view of plain or solid heater. Fig. 4 is a transverse section through case. Fig. 5 is a horizontal or plan view of slide and part of case. Figs. 6 and 7 are, respectively, side and plan views of modification of ferrule for handle.

The nature of my invention consists in the novel construction and combination of parts, as hereinafter fully set forth.

Referring to the accompanying drawing, A is the case, which is formed with a projection or point, a' , for ironing around buttons without rumpling the garments to which said buttons are secured. The bottom of the case A is thicker at the sides than at the center, allowing the heat to pass rapidly through the latter, and equalizing the temperature of the face of the iron, which is hottest usually at the corners or edges when taken from the fire. The face of the case A is convex or rounded at the edges, so as to glide easily over seams and uneven surfaces. B B' are the heaters or cores, of which there are four, two heavy and two light, the weight of the latter being reduced by being made hollow or with an opening, b' , through them. The light and heavy heaters are of the same size, so as to fit in the one case. For ordinary purposes the two heavy heaters will be sufficient, one being heated in the fire while the other is in use ironing. When fancy work, as ruffling, is required to be done, the light heaters will be used. The heaters B B' are formed with beveled or rounded faces, adapting them to the shape or curvature of the case, and preventing them from warping or twisting while in the fire. C represents the cover, which is

made with a slide lock or lever, C', for engaging with and raising the heater out of the fire, and for fastening the heater and case together. D represents a knob or handle, (for which a straight bar may be substituted,) by means of which the slide C' is operated. D' is the shaft, to which the handle D is attached, having a short arm, d, with a pin, d' , which enters a circular opening in the slide, so that when the handle D is turned the slide will be moved longitudinally. d'' is a cleat fastened to the top of the cover, and fitting in an elongated slot in the slide C', preventing any lateral movement of the latter. E is a cover for the slide, having a central opening for the passage of the shaft D', but being made tight and close, so as to prevent as much as possible the escape of heat from the case A. F is a shield or plate, to which the handle G is attached, said plate being secured to the cover by any suitable means which will produce but small contact of surfaces, so as to avoid the transmission of heat to the handle. I have illustrated it as connected to the cover by hooks f in front, and by an inverted arch, f' , and screws f'' in the back. The handle G, which is made of turned or bent wood, is fitted in skeleton or open metallic ferrules H H', provided with buttons h h' , which pass through openings in the plate F, the button h , with its ferrule, sliding forward after insertion, and the button h' following and turning around. The ferrules H H' are made open, so as to produce columns or points of slight surface-contact, and are also beveled, as shown at h^5 , where they touch the wooden handle, for the same purpose. The handle and ferrules are held firmly together by means of screws passing up through the bottom of the latter, or by rivets through the sides. The base of one of the ferrules is composed of a disk, h^2 , having a groove, h^3 , in which the legs of the ferrule stand. h^4 is a screw, by which said disk and legs are kept in contact, the former turning freely on the smooth neck of the screw. The under side of the slide C' is furnished with cleats c c , so as to have but slight surface-contact with the cover, and the upper side is grooved, so as to form sharp-edged ridges for contact with the catches on the posts a a and b b , rising from the case and heater, respect-

ively, the object being to prevent the transmission of heat to the handle.

The operation is as follows: The handle, plate, and cover, being duly connected together, are put down over the heater, the posts on the latter passing through the openings in said cover. The knob or handle D is then turned, bringing the slide under the catches on the posts b b, thereby engaging the heater, which is now lifted into the case, the posts in the latter passing through the openings in said heater. The handle or knob D is then turned in an opposite direction, engaging with the catches on the case-posts a a, locking the case and cover together.

I design making the case of a prepared cast-iron, of harder and finer grain than the common material, and which will admit of a higher polish and smoother face than the latter. The posts a a will be of malleable iron, and will be inserted in the molds, so that the iron of the case will be cast around them.

The knob D is operated by the thumb and finger of the hand that holds the handle of the iron, and, being situated in the center, or between the two points where the handle is attached to the cover, is in a position that is always convenient to be operated. The slide-lever and handle are so constructed and operated that they are not liable to become unfastened or displaced by a sudden movement, or by accidental hitting with the hand or garments, thereby removing the defect of dropping the hot case or heater, and burning the garment, as is frequently done with irons of this class of a different construction from mine.

The tight cap for the slide, and the slight points of contact of the slide, cover, handle-plate, and handles, prevent in a marked degree the transmission of heat to the handle, thereby effectually preventing the burning of the latter. The operator's hand is also shielded by the plate F, and the open ferrules permit a free circulation of air under the end of the handle—these features all uniting to make an iron which will retain the heat in the case, and permit the necessary radiation through the bottom, while protecting the operator's hand

and the handle of the iron from being burned. The detachability of the handles will be found a benefit in transporting the irons, enabling the parts to be separated and packed in small compass.

What I claim as my invention is—

1. The longitudinally-reciprocating slide C', constructed and adapted to operate substantially as described, in combination with the posts a b, attached to the heater and case, respectively, for the purpose specified.
2. The combination of the longitudinally-reciprocating slotted slide C', posts a a b b, lever d, and shaft D', substantially as shown and described.
3. The reciprocating slotted slide C', having the cleats c c, in combination with the plate C, substantially as described.
4. In combination with the handle-plate F, the removable handle G, substantially as described.
5. The combination, with the handle-plate F and cover C, of the skeleton supports interposed between them, substantially as described and shown.
6. The heater B', having the opening b', as and for the purpose shown and specified.
7. The combination of the non-metallic handle G, open or skeleton ferrules H', attached to the ends thereof, and the handle-plate F, substantially as shown and described.
8. In combination with the longitudinally-reciprocating slide C', the shaft D', having the knob or handle D, and the arm d, as set forth.
9. The ferrule H, having the revolving disk h², as shown and described.
10. The combination, with the handle G, of the ferrules H H', having their upper ends beveled at h⁵, as shown, and for the purpose specified.

In testimony that I claim the foregoing I have hereunto set my hand this 3d day of February, 1874.

WILLETS MACOMBER.
